METHOD OF MANUFACTURING FABRICS HAVING A SUPPORT BACKING AND UP- STANDING PILE

Georges C. Ahier, Alfred V. Champagnat, and
Jean F. M. Tirmont, Paris, France

Application December 29, 1947, Serial No. 794,290
In France January 3, 1947

5 Claims. (Cl. 154—78)

1

A corded material (carpet, velvet, etc.,) is comprised essentially by a support or backing of woven textile fibers and by U-shaped cords knotted or attached to the backing by textile threads. A very common method consists in previously manufacturing chenilles which are made up of U-shaped cords tied together in a straight line by several textile fibers. The chenilles are then fixed on the backing by a system of textile knots.

Figure 1 shows a chenille constituted by U-shaped cords 1 tied together by textile threads 2 and 3.

These manufacturing methods are very slow, complicated and require a huge amount of threads and an important work force. Thus the products are of a high cost.

The object of the present invention is to obviate these various drawbacks.

It concerns a method for the manufacture of materials or similar products, especially carpets, in which the chenille is fixed on its support by gluing, which makes it possible to obtain products superior to those manufactured at present, while allowing a considerable saving in textile threads, a great simplicity and a high speed of manufacture, as well as an important reduction of the necessary work personnel. By an appropriate choice of the backing, the strength of the product, its soundlessness and its adherence to the floor are also increased.

In accordance with one type of embodiment of the invention, the chenilles are attached by gluing to a support or backing.

In accordance with a modification, the chenilles are themselves manufactured by gluing, before being attached by gluing to the support or backing.

The invention extends not only to the above methods, but also, by way of new industrial products, to textile products similar to those obtained by previous methods, such as chenilles, materials, carpets and such products.

The invention also extends to other characteristics described hereinafter and to their various possible combinations.

Products according to those obtained by the method and installations for carrying out the method are described by way of non-limitative examples and with reference to the appended drawings wherein:

Fig. 2 shows a warp and a woof used for the manufacture of a chenille in accordance with the invention.

Fig. 3 is a view, in perspective, of a chenille mounted on a thread.

Fig. 4 is a view in perspective of a chenille mounted on two threads.

Fig. 5 is a view in elevation of an apparatus for the fixation of the chenilles on their supports.

A method in accordance with the invention is

2

described hereinunder by way of non-limitative example in the manufacture of a chenille by gluing.

A textile thread is previously coated with rubber latex to which the appropriate ingredients for vulcanization have been added, for instance, zinc oxide 5%, sulphur 2%, accelerator 1%, anti-oxygen 1%, with respect to the rubber.

This coating may also be made with emulsions of polyvinyl-chloride or its copolymers, super-polyamides, etc., solutions may also be used of synthetic resins of various kinds, or other adhesives, or these adhesives or melted resins softened or plasticized, etc., may be used.

A grid or quadrille is formed by the superposition of a sheet of textile threads coated with rubber base glues, synthetic resins, etc., and a sheet of wool threads or other uncoated textiles, for forming the cords proper. By means of a slight pressure, a sufficient gluing is obtained between the coated and the uncoated threads.

Figure 2 shows a schematic view of the glued canvas in accordance with the invention, *xx'* (and the threads parallel thereto) are the threads coated with adhesives, *yy'* (and the threads parallel thereto) are the uncoated threads for forming the cords. Once the gluing has been effected, the threads *yy'* are cut at *AB*, *A'B'* in accordance with the conventional method of the textile industry for the manufacture of chenilles for sieves. The sheet of chenilles thus obtained then goes through a fluted cylinder, heated, which bends the cord threads in the shape of a U.

The chenille obtained is schematized on Figure 3. The thread (or threads) which are coated, *F*, is (or are) glued inside the U with glue *a*, which ensures a greater strength.

By the same method, a chenille may also be manufactured comprising two or more coated threads, one (or the ones) *F* glued inside the U with glue *a*, the other (or others) *F'* outside, with glue *a'*, which facilitates the gluing of the chenille on the backing (Figure 4).

The method also applies to the fixation by gluing of the chenilles thus obtained or any others, on any support or backing.

The chenilles thus used may be manufactured as indicated above. They may also be manufactured without any gluing by the conventional methods of the textile industry or any other method.

The chenilles are generally coated, at their bases, with a rubber latex, an emulsion or a solution of an adhesive or any other gluing agent, consistent with the glue and support adopted.

Some particularly advantageous types of support or backing are given hereinafter by way of example.

(a) A simple backing woven of textile or felt is coated or impregnated with rubber or synthetic resin or any other gluing product.

(b) There may also be used as a backing a rubber band, vulcanized or not, loaded or not with various textile or non-textile loads or both. It is also possible to choose rubber, vulcanized or not, reinforced by isolated textile fibers, or arranged in parallel sheets, of canvas or material, etc. The same combinations may be made with any kinds of synthetic resins, polyvinyl chloride and their co-polymers, superpolyamides, etc. Alternately, it is possible to use more or less flexible plates of agglomerates of any kind, such as, for instance, those of sawdust, meal, chips or wood fiber, wool or glass fiber, cork, alpha etc., linoleum, dummies, etc.

(c) A very important modification consists in using as a backing a band of non-vulcanized rubber, the composition of which includes a suitable proportion (1 to 5% or more) of a substance such as diazoaminobenzene which is decomposed during the final vulcanization of the finished material, giving a spongy, flexible and low density structure. Finally, such a backing can be obtained in large thicknesses and its compressibility is a very interesting property for a corded material, particularly for carpets. With an equal thickness, products are thus obtained of an unusual lightness and flexibility and of a very low manufacturing cost.

(d) The backing can also consist of spongy rubber, so-called sponge rubber, pre-vulcanized.

(e) It is also possible to choose as a backing, synthetic resins or plastic materials made spongy by the same method, polyvinyl chloride and its co-polymers, superpolyamides etc.

(f) In the case of the use of these spongy rubbers or synthetic resins, it is advantageous, to increase the tearing resistance, to reinforce them by a material, a canvas, or simply by parallel textile fibers, which are fixed by gluing, previously or during the gluing of the chenilles on the backing.

(g) For making the backing there may also be used any other suitable materials offering the necessary mechanical qualities and capable of being glued to the chenilles, such as, for instance, agglomerates of silicates or coal tar, of petroleum, etc. made of wood meal, wool, cotton, glass fibers, cork, etc.

The chenilles, arranged parallel and as close as desired are glued onto the backing by a slight pressure.

In each case, the glue which is most appropriate for the coating of the chenilles and for the corresponding backing is used. For instance, it is preferable, for gluing the chenilles coated with rubber, or with synthetic resins on the backing of a similar nature, to select a glue of the same kind. One can also use, however, one or several intermediate suitable adhesives.

Particularly advantageous embodiments of the invention are given hereinafter by way of non-limitative examples:

(a) Chenilles of the conventional type obtained by weaving, and a woven textile backing.

The bases of the chenilles arranged in sheets were coated with rubber latex containing the ingredients for vulcanization. The backing was also coated on one face with the same vulcanizable latex. Before or after drying, the chenilles are pressed against the backing to cause the gluing. Vulcanization is then effected. Wool, for instance, stands very well the thermal vulcanization treatment for the rubber. Thus, the fixation of the chenilles on the backing by the conventional methods of the textile industry,

which is the most costly and slowest part of the manufacture of carpets, is avoided.

By using chenilles made of cord threads of different colors, selected and arranged at will, as for the conventional carpets, corded materials with designs can be obtained.

The chenilles thus attached to the backing are attached more strongly than by the conventional method, and the materials manufactured in accordance with the invention can be cut along any direction, which is not the case for the conventional chenille materials.

(b) Chenilles manufactured according to the method of the invention and backing of non-vulcanized rubber.

On one hand, a mixture of rubber with the plasticizer, filling, sulphur, zinc oxide, accelerator and anti-oxygen was prepared. It was then press rolled to obtain a band, the width of which

20 was equal to that desired for the backing.

On the other hand, the chenilles according to the method of the invention were coated, at their bases, with a rubber latex of the same kind, natural or artificial, as that constituting the 25 backing. In particular, the latex must contain the same accelerator as the backing, for its vulcanization.

After drying of the latex, the chenilles, arranged parallel in sheets, and as close as necessary, were pressed with a slight pressure against the 30 backing, which ensured the gluing. Vulcanization was then effected.

One modification consists in coating, on one 35 face, the rubber backing with benzol or naphtha solvent, which improves its gluing power. The chenilles coated with latex and dried, or even uncoated are strongly glued by simple pressure on the backing thus coated. One ends again by a vulcanization.

40 To the rubber mixture of the backing may be added a substance which is decomposed during the vulcanization, releasing gases, which produces a rubber having a cellular or spongy structure.

Materials with designs may also be obtained 45 as indicated in the above type of embodiment.

(c) Chenilles manufactured according to the method of the invention and a vulcanized rubber backing.

The chenilles were prepared as in the above 50 type of embodiment, by impregnation of their bases with a vulcanizable latex.

The backing was made rough, on one face, by mechanical abrasion, then coated with a vulcanizable rubber cement containing a rubber of the same kind, and the same vulcanization accelerator as the latex of the chenilles. Chlorinated rubber may also be incorporated in this cement.

55 After part of the solvent of the cement had evaporated, the chenilles were fixed by pressure on the face of the backing coated with cement. The drying was then effected and the vulcanization made. Spongy or cellular rubber can also be used as a backing.

The methods described can be realized on an industrial scale with a material suggested by the techniques used in the rubber industry for the coating of materials and by the weaving industry.

60 An apparatus for the gluing of the chenilles on their backings is described hereinafter by way of example (Figure 5).

The apparatus comprises:

A fluted cylinder 4 for driving the chenilles and regulating their spacings.

Cylinders 5 and 6 for driving and stretching the backing.

A cylinder 7 and toothed cylinders 8 and 9.

A free toothed cylinder 10 for guiding the material.

A driving cylinder 11.

A tunnel oven 12 for vulcanization.

The apparatus operates as follows:

The sheet of chenilles 13 comes from the manufacture, the threads being coated with latex as indicated in Figure 4. The sheet is driven by cylinder 4 which, at the same time, regulates the spacing of the chenilles.

The non-vulcanized rubber web forming the backing unrolls at 15, it is driven and stretched by cylinders 5 and 6.

The sheet 13 and the backing 15 are applied and glued one over the other by means of the pressure exerted on cylinder 7 by the toothed cylinders 8 and 9.

The material 16 is guided and driven by the cylinders 10 and 11 inside the tunnel oven 12 where the vulcanization of the latex is effected.

The finished material 17 goes out at the end of the oven. The tunnel oven 12 may be replaced by a stove wherein the material is suspended from horizontal bars.

Numerous modifications may be made to the above described examples without exceeding the scope of the invention and especially, multiple applications of this invention can be devised.

The invention extends not only to the above methods but also by way of new industrial products, to textile products similar to those obtained by the above methods such as chenilles, materials, carpets and the like.

In the text of the present specification and especially when dealing with the threads used for the manufacture and/or the fixation of the chenilles, the word "textile" must be understood to apply as well to artificial textiles such as artificial silk, polyamides, vinylic resins, etc. and their likes.

We claim:

1. A process of manufacturing fabrics having a support backing and upstanding pile comprising forming a first sheet of adhesive coated parallel warp threads, placing on the first sheet a second sheet of uncoated pile threads parallel to each other and transverse to the warp threads, pressing the threads of the second sheet against the threads of the first sheet to bond them together, cutting the threads of the second sheet between adjacent threads of the first sheet, bending the cut pile threads into U-shape about the warp threads to form a sheet of parallel chenilles in which the free ends of all of the pile threads extend from the same side of the sheet of chenilles and in which the warp threads constitute the opposite side and base of the chenilles, coating the base of the chenilles with an adhesive and contacting the coated base with a support backing to bond the chenilles to the backing.

2. A process of manufacturing fabrics having a support backing and upstanding pile comprising forming a first sheet of adhesive coated parallel warp threads, placing on the first sheet a second sheet of uncoated pile threads parallel to each other and transverse to the warp threads, pressing the threads of the second sheet against the threads of the first sheet to bond them together, cutting the threads of the second sheet between adjacent threads of the first sheet, passing the sheet of warp threads carrying the cut pile threads through grooves in a heated cylinder

thereby bending the cut pile threads into U-shape about the warp threads to form a sheet of parallel chenilles in which the free ends of all of the pile threads extend from the same side of the sheet of chenilles and in which the warp threads constitute the opposite sides and base of the chenilles, coating the base of the chenilles with an adhesive and contacting the coated base with a support backing to bond the chenilles to the backing.

3. A process according to claim 1 in which the adhesive coating the parallel warp threads of the first sheet is of a vinyl resin base.

4. A process of manufacturing fabrics having a support backing and upstanding pile comprising forming a first sheet of adhesive coated parallel warp threads, placing on the first sheet a second sheet of uncoated pile threads parallel to each other and transverse to the warp threads,

20 pressing the threads of the second sheet against the threads of the first sheet to bond them together, cutting the threads of the second sheet between adjacent threads of the first sheet, bending the cut pile threads into U-shape about the warp threads to form a sheet of parallel chenilles

25 in which the free ends of all of the pile threads extend from the same side of the sheet of chenilles and in which the warp threads constitute the opposite side and base of the chenilles, coating the base of the chenilles with an adhesive and contacting the coated base with a support backing formed of a sheet of non-vulcanized rubber, the surface of which is coated with a softening solvent to give it an adhesive power and effectively bond the base of the chenilles to the backing.

30 5. A process of manufacturing fabrics having a support backing and upstanding pile comprising forming a first sheet of adhesive coated parallel warp threads, placing on the first sheet a second sheet of uncoated pile threads parallel to each other and transverse to the warp threads,

35 pressing the threads of the second sheet against the threads of the first sheet to bond them together, cutting the threads of the second sheet between adjacent threads of the first sheet, bending the cut pile threads into U-shape about the warp threads to form a sheet of parallel chenilles

40 in which the free ends of all of the pile threads extend from the same side of the sheet of chenilles and in which the warp threads constitute the opposite side and base of the chenilles, coating the base of the chenilles with an adhesive and contacting the coated base with a support backing formed of a sheet of synthetic resin to bond

45 the base of the chenilles to the backing.
